United States Patent Office.

GEORGE H. BAILEY, OF JERSEY CITY, NEW JERSEY.

Letters Patent No. 64,187, dated April 30, 1867.

IMPROVED MACHINE FOR MAKING WATER, GAS, AND OTHER PIPES.

The Schedule referred to in these Letters Patent and making part of the same.

TO ALL WHOM IT MAY CONCERN:

Be it known that I, GEORGE H. BAILEY, of Jersey City, Hudson county, State of New Jersey, have invented a new and improved Machine for Making Water, Gas, and Sewerage Pipes; and I do hereby declare that the following is a full, clear, and exact description thereof, reference being had to the accompanying drawings, making a part of this specification, in which—

Figure 1 is a section taken in a vertical plane through the centre of the machine showing the plunger elevated.

Figure 2 is a similar view of the same parts showing the plunger depressed.

Figures 3 and 4 are sectional views taken in horizontal planes through the machine.

Figures 5 and 6 represent a plunger with spiral cutters formed on its conical end.

Similar letters of reference indicate corresponding parts in the several figures.

This invention relates to an improvement on the manufacture of pipes, which are formed either of a combination of iron and cement, or of cement only; and it consists in subjecting the material composing the pipe to powerful pressure whilst in a plastic state, thereby greatly increasing the strength and solidity of the same, and facilitating the manufacture.

To enable others skilled in the art to understand my invention, I will describe its construction and operation.

In the accompanying drawings, A represents the pipe to be lined, or the mould to be filled, as the case may be. It is set in an upright position on the bed-plate B, and kept in place by means of rings or collars C C'. D is a smooth, polished plunger, of the exact size of the inner bore of the pipe when finished, and somewhat longer than such pipe. It is made to travel in a vertical direction by means of the cross-head E, on the guide-rods F F, which latter are supported by the framework G. The plunger D works through the upper ring or collar C, which is bored out so as to allow this plunger to move freely, and which is recessed on the under side to receive the upper end of the pipe A, as shown in fig. 2. This collar C is kept in position by the guide-rods F F, and works freely up and down on them. The lower end of the plunger terminates in a cone, which may have spiral cutters, a a, formed on it, as shown in figs. 5 and 6. The bed-plate B is recessed to receive the conical end of the plunger, and is perforated with an opening, b, which may be provided with a valve or plug so that it can be opened or closed at pleasure. When set in proper position the centres of the cross-head E, collar C, and bed-plate B, are all in the same vertical line. The upper collar C has a series of small openings or notches, e e, extending from the upper end of the pipe A to the top side of the collar. The plunger may have applied to its upper end a screw, or lever, or any convenient arrangement of power for forcing it down. A screw, G', is represented in the drawings working through a nut in the cross-head. When power is applied to depress the plunger, bolts d d are inserted through the standards of frame G above the cross-head, and the collar C, at the top of the pipe A, is secured in like manner. Two rods g g are attached to the under side of the cross-head E, and pass through the supporting-bar of the collar C, with adjusting nuts on their lower ends, as shown at h h, in figs. 1 and 2. These rods are of such length as, when the pipe is completely lined and the plunger elevated to a sufficient height, to raise the top collar C from the top of the pipe.

The operation of forming a pipe is as follows: The iron pipe A to be lined, or the mould to be filled, as the case may be, is set on the bed-plate, the plunger being raised entirely free from the pipe by means of a crane or windlass. The hole at the bottom is closed by a plug or valve, and a sufficient quantity of cement thrown in to form the pipe. The plunger is lowered sufficiently to allow the upper end of the pipe to enter the recess in the lower side of the collar C, and when thus adjusted the plunger is allowed to fall rapidly, displacing the cement in front of it. As the means of escape at the bottom is closed the cement is forced to rise, filling the space between the plunger and the pipe or mould. The plunger by its own weight and the momentum acquired will enter some distance into the soft cement. As soon as the plunger has ceased to fall, the bolts d d are inserted above the cross-head, and the power applied, forcing the plunger to pass entirely to the bottom of the pipe until it strikes the bed-plate. If, at the same time, the plunger is turned about its axis, the advantage is gained of rubbing down the surface of the cement, greatly aiding in compacting and smoothing it. The advance of the plunger will be facilitated by the application of spiral cutters to the lower end. As the pipe

fills with cement the air is driven out through the vents *ee*, through the collar *C*, and the filling of the pipe is indicated by the escape of cement through the same openings. These openings may be closed when the pipe is entirely filled, and the whole power applied for compressing the cement, or the surplus discharged through the vent below. To prevent the cement setting fast to the plunger, it is occasionally turned until the cement is sufficiently set to maintain its shape, when it is withdrawn, the vent at the bottom being first opened to prevent a vacuum being formed under the plunger.

In the above description I have set forth the power used for forcing the plunger down as a screw. I do not, however, confine myself to the screw, as steam or other convenient power may be applied without affecting the principle of my invention. The form given to the end of the plunger assists it in displacing the cement, and at the same time gives a certain means of exactly centering the plunger when it reaches the bottom.

The operation and effect will be substantially the same by reversing the arrangement of parts; that is to say, the plunger may remain stationary, or have only a rotary motion, and the pipe charged with cement forced down by power applied to the upper end of it. Whilst the principle herein set forth is applicable to the formation of pipes composed in whole or part of plastic material, of whatever form, it is peculiarly adapted to the manufacture of pipes composed of iron and cement made in the well-known form of Knight's patent, in which the iron is formed with a taper, giving when lined a greater thickness of cement at one end than at the other. By the method herein described, the pipes being lined with the largest ends down, and the cement being forced upward from the bottom to the top, it is constantly pressed into a contracted space, and must necessarily be greatly compressed. The cement can escape at the top only when all the space below has been filled. The object aimed at and attained by my invention is to furnish a more solid and perfect pipe than can be made by any of the methods now in use. By the method of lining with the core drawn through the pipe, which is the one in common use, the cement is simply laid against the iron pipe or mould by the rapid passage of the core without being subjected to any considerable pressure, and consequently the lining is liable to drop off and settle toward the bottom of a pipe while in a green state, leaving spaces to be patched by hand.

Having described my invention, what I claim as new, and desire to secure by Letters Patent, is—

1. The employment, in the manufacture of pipes composed in whole or in part of cement or plastic material, of a plunger, either movable or stationary, which is shaped substantially as set forth, either with or without spiral cutters, and which by the application of power or by its own weight and momentum displaces the cement in front of it, causing the latter to adhere to the pipe, and rendering it solid and compact, substantially as described.
2. The combination, with the plunger *D*, of the top and bottom collars *C C'*, with vent holes for the admission and escape of air, substantially as described.
3. The application of lifting-rods *gg* to the collar *C*, for lifting this collar when the plunger is raised, substantially as described.
4. I claim a plunger working within a metallic pipe or mould, having one or both ends closed so as to more perfectly and forcibly compact the cement or plastic material within it, substantially as described.

GEO. H. BAILEY.
